UNITED STATES PATENT OFFICE.

JOHN L. HIGHBARGER, OF SHARPSBURG, MARYLAND.

BOOK-HOLDER.

SPECIFICATION forming part of Letters Patent No. 223,589, dated January 13, 1880.

Application filed October 13, 1879.

To all whom it may concern:

Be it known that I, JOHN L. HIGHBARGER, of Sharpsburg, in the county of Washington and State of Maryland, have invented a new and Improved Book-Holder; and I do hereby declare that the following is a full, clear, and exact description of the same.

The object of my invention is to provide an improved portable device for holding books open for convenience of reading. The device is applied to the upper end of a book-cover; and it consists mainly of three parts, to wit: a bar or roller, two hooks or clasps, and two bent pivoted fingers. The hooks and fingers are attached to the ends of said bar or roller. The hooks or clasps receive and tightly clamp the upper edges of the lids of the book, and are so attached to the bar or roller that the latter is free to rotate. The pivoted fingers revolve with the roller, so that they may be turned into suitable position to enable them to hold the leaves of the book, as hereinafter more fully described.

In the accompanying drawings, forming part of this specification, Figure 1 is a front view of a book and my improved holder attached. Fig. 2 is a vertical cross-section on line xx , Fig. 1. Fig. 3 is a rear view of a portion of a book with my holder attached.

A is the bar or roller, which may, if desired, be made of various lengths. The spring hooks or clasps B are made of wire or thin metal plate, and attached to the roller A near its ends by loops or other means, so that the roller is free to rotate therein. The said clasps are approximately S-shaped, or doubled on themselves, so as to form slotted holders for the edges of the book-cover, as shown in Fig. 1. A plate, C, rigidly connects the clasps and forms the support for the hinge of the book-cover. The fingers D are bent at a right angle and pivoted to the roller A at points contiguous to the hooks B. The outer ends of the fingers are curved, and rubber pads a are ap-

plied to their tips, for the purpose of enabling them to hold the leaves of the book in place by friction therewith without injury.

An arm, E, is rigidly attached to the roller A, as shown, to enable the roller to be conveniently rotated after the device has been applied to a book-cover, as shown in Fig. 2, for the purpose of bringing the fingers D into position to hold the leaves of the book in place. As the reading of the pages progresses the leaves may be successively drawn from under the padded end of one finger and turned and inserted under the end of the other finger with convenience and dispatch.

In order to better secure the device to a book, I may employ the hooks F, which are attached to the clasps B by means of elastic bands. These hooks F are applied to the lower edges of a book-cover, and the elasticity of the bands enables them to be used on books differing in length.

The device is small, light, and compact, and is hence easily portable. It may be used on books held in racks, or it may be attached to a standard or other form of support, as when required for use for holding band-music books. For this purpose a socket, b, is formed on or attached to the back of plate C, to receive a standard or other object on which the device is supported.

I do not claim a book-holder consisting of a bar having elastic fingers and rigid clasps for clamping the leaves and covers of a book; but

What I claim is—

The improved portable book-holder hereinbefore described, consisting of the spring-clasps B, for attachment to book covers or lids, the plate C, which connects the same, the bar A, which is free to rotate, and the fingers pivoted thereto, all as shown and described.

JOHN L. HIGHBARGER.
